COMBINED FILTER AND REGULATOR FOR PRESSURIZED FLUID

Claude J. Dussardier, Littleton, and John G. Pousma,
Denver, Colo., assignors to C. A. Norgren Co., Little-
ton, Colo.

Filed Oct. 4, 1973, Ser. No. 403,544

Term of patent 14 years

Int. Cl. D23—01

U.S. Cl. D23—04

FIG. 1

FIG. 2

FIG. 3

FIG. 4

FIG. 1 is a perspective view of a combined filter and regulator for pressurized fluid showing our new design;

FIG. 2 is a top view thereof;

FIG. 3 is a side elevational view thereof;

FIG. 4 is a bottom view thereof; and

FIGS. 5, 6 and 7 are additional side elevational views thereof.

We claim:

The ornamental design for a combined filter and regulator for pressurized fluid, as shown.
